DISPENSING MEANS FOR PELLETS

Howard J. McLaughlin, Port Orchard, Wash., assignor of one-half to James B. Hussey, Port Orchard, Wash.

Application May 14, 1946, Serial No. 669,504

3 Claims. (Cl. 312—49)

1

My present invention relates to dispensing means for pellets which is intended for general use as distinguished from those devices which are coin operated. My present dispenser is designed so as to accurately dispense pellets, one at a time, and is so constructed that easily deformed, crushed or brittle spheres, cubes, and the like may be stored under conditions protecting them from local contamination and especially to prevent the contamination of the stored pellet from handling by persons having normal rightful access to the pellets stored.

The principal object of my invention is to provide a dispensing device which will accurately dispense one pellet at a time.

A further object of my invention is to provide a dispenser in which the feeding of pellets will be continuous without stoppage until they are all consumed.

A further object of my invention is to provide means whereby the feeding of pellets through my machine can be accurately accomplished whether the dispenser is full or practically empty.

Further objects, advantages, and capabilities will be apparent from the description and disclosure in the drawings which are inherent in the device.

In the drawings:

Fig. 1 is a perspective view showing the dispensing side of my device;

Fig. 2 is a vertical view, in section, taken on a plane through the dispensing mechanism of the device;

Fig. 3 is a vertical sectional view similar to Fig. 2 but showing my device in an advanced stage of its functioning;

Fig. 4 is a view similar to Figures 2 and 3 with upper portion broken away and showing the final stage in the cycle of operation;

Fig. 5 is a vertical sectional view with the lower portion of the housing broken away, taken along line 5—5 of Fig. 2;

Fig. 6 is a perspective view showing the pivoted dispensing lever;

Figs. 7 and 8 are cross sectional views, in plan, taken along similarly numbered lines of Fig. 2;

Fig. 9 is a cross sectional view, in plan, taken along the line 9—9 of Fig. 3;

Fig. 10 is a vertical sectional view taken along the line 10—10 of Fig. 3 with the upper part of the housing broken away;

Fig. 11 is a bracketed view showing three of the preferred forms of pellets for use with my device.

Referring more particularly to the disclosure 55

2

in the drawings, the numeral 12 designates generally the main body portion of the housing I employ with my device. This is provided with the tight-fitting bottom closure 13 and the cover member 14. Disposed within the lower portion of housing member 12, and preferably made as a part thereof, is a hopper arrangement composed of the inwardly sloping surface 18 which is disposed at right angles to surfaces 16 and 17. The hopper sides 16 and 17 terminate in the trough-like chute 20.

Pivots disposed, as on pin 22, is the dispensing lever 23. This member is provided with a finger rest 24, a pellet receiving cavity 25, and the arcuate stop member 26. At the extreme end of member 23 is the separating member 27 which is arcuate in form and adapted to pass through opening 28 in trough 20. The dispensing lever 23 is so positioned that pivot pin 22 is wholly within the housing and supported by the spaced bosses 30 and 31. This leaves only the finger-engaging portion 24 and cavity 25 outside the housing.

Method of operation

25 In operating my device, it first must be filled by removing cover 14. The pellets, as they are placed within the storage or upper portion 33 of my dispenser, will rest upon the hopperlike bottom and will be directed by the sloping bottom members 16, 17, and 18 into the dispensing groove 20. Groove 20 must of necessity be proportioned in keeping with the size and shape of pellets to be dispensed. Throughout the drawings I have illustrated round or spherical pellets. However, 30 cubes of sugar or modified cubes after the showing of Fig. 11 can all be depended upon to feed through my dispensing mechanism with certainty.

When it is desired to dispense a pellet, pressure is applied, as by the finger, to portion 24 of the dispensing lever. As that portion of the lever is pressed downwardly the lever revolves about pivot 22, and two actions occur: first, the stop member 26, which has an arcuate surface with the pivot 22 as its center and a downwardly extending portion 34 swings upwardly and across the discharge opening 36, and in this way assures that only one pellet will be discharged, the remaining pellets coming to rest on the arcuate surface of stop 26.

Long trials and experiments with dispensers 45 have indicated the necessity of having some means of preventing the pellets from bridging over and thus not feeding through the discharge opening, and also if the feeding or dispensing is to be done with certainty, the pressure of the mass of pellets above the discharge opening should

be taken off of the pellets next to be dispensed. In my drawings I have illustrated a member which has been found to serve this purpose fully, that is, the load supporting arcuate member 27, which is formed as part of lever 23 and has the arcuate portion formed with its center of generation at pivot 22. This member 27 swings upwardly through opening 28 as the dispensing lever is revolved to the dispensing position, and by its movement through the mass of pellets will break up any attempt at bridging over, and as soon as it has reached the position as shown in Fig. 4, it prevents any of the mass above the dispensing opening from placing any pressure on the pellets P which are next to be dispensed. It will now be observed that the two pellets, one resting upon the arcuate surface of stop 26 as shown in Fig. 4, and the one next above it, are relieved of all pressure and will then function smoothly through my device under the urging only of gravity.

Here it is desired to point out that the sloping surface 18 in co-action with the movable separating member 27 assures the breaking up of any lodgment which might otherwise occur immediately above the discharge opening 36. In the various views I have illustrated the details of construction of the sloping surfaces 16, 17, and 18 quite fully, as the successful operation of this device depends very largely upon the observation of these proportions.

It is believed that it will be apparent from the above description and the disclosure in the drawings that the invention comprehends a novel construction for a dispensing device, which is simple and positive in operation and is extremely sanitary in use. Furthermore, due to this novel construction and arrangement, the parts of the dispensing mechanism are self cleaning of any fragments or broken pellets, as any fragmentation is free to slide down under stop member 26 and come to rest in the lower portion 35 of my housing, where they may from time to time be disposed of through closure 13.

What I claim is:

1. A dispensing means for pellets comprising a housing body having a discharge opening; a top closure for said body; a bottom closure for said

body; a hopper formed in said body composed of two inwardly sloping sides terminating in a centrally disposed trough which slopes downwardly to said discharge opening; a dispensing lever pivotably disposed in said discharge opening, said lever having an arcuate separating member adapted to operate through a hole in the bottom of said trough, an arcuate stop adapted to coact with said discharge opening to provide one at a time dispensing of pellets, and a pellet arresting cavity disposed outside the housing.

2. A dispensing means for pellets comprising a housing body having a discharge opening; a top closure for said body; a bottom closure for said body; a hopper arrangement secured substantially midway in said body composed of two inwardly sloping sides terminating in a centrally disposed trough which slopes downwardly to said discharge opening; an inwardly directed sloping surface disposed above said discharge opening and adapted to discharge materials into said trough; a pivoted dispensing lever, a separating member operated by said lever and adapted to operate in said trough; a stop operated by said lever and adapted to coact with said discharge opening to provide one at a time dispensing of pellets, and a pellet arresting cavity disposed outside the housing.

3. A dispensing means for pellets comprising a housing body having a discharge opening; a top closure for said body; a bottom closure for said body; a hopper arrangement secured substantially midway in said body composed of two inwardly sloping sides terminating in a centrally disposed trough which slopes downwardly to said discharge opening; an inwardly directed sloping surface disposed above said discharge opening and adapted to discharge materials into said trough; a dispensing lever pivotably disposed in said discharge opening, said lever having an arcuate separating member adapted to operate through a hole in the bottom of said trough, and an arcuate stop adapted to coact with said discharge opening to provide one at a time dispensing of pellets, and a pellet arresting cavity disposed outside the housing.

HOWARD J. McLAUGHLIN.
